US00D482124S

(12) **United States Design Patent** (10) Patent No.: **US D482,124 S**
(45) Date of Patent: **** Nov. 11, 2003**

(54) **ELECTRICAL NEUROMUSCULAR STIMULATOR**
(75) Inventor: **Alan L. Wade**, Huntington Beach, CA (US)
(73) Assignee: **VQ Orthocare**, Irvine, CA (US)
(**) Term: **14 Years**
(21) Appl. No.: **29/173,238**
(22) Filed: **Dec. 23, 2002**
(51) LOC (7) Cl. **24-04**
(52) U.S. Cl. **D24/200**
(58) Field of Search **D24/200; 607/39-46, 607/48, 49, 64, 66, 72; 600/546**

(57) **CLAIM**

The ornamental design for an electrical neuromuscular stimulator, as shown and described.

DESCRIPTION

FIG. 1 is a front perspective view of the electrical neuromuscular stimulator of the present invention showing my new design,

FIG. 2 is a left side elevational view thereof,

FIG. 3 is a front elevational view thereof,

FIG. 4 is a right side elevational view thereof,

FIG. 5 is a top plan view thereof,

FIG. 6 is a bottom plan view thereof; and,

FIG. 7 is a rear elevational view thereof.
